(57) **CLAIM**

The ornamental design for a bottle, substantially as shown and described.

DESCRIPTION

FIG. 1 is a perspective view of a bottle in accordance with our new design;

FIG. 2 is a front elevational view thereof with the back elevational view being a mirror image thereof;

FIG. 3 is a left side elevational view thereof, right elevational view being a mirror image thereof;

FIG. 4 is a top plan view thereof; and,

FIG. 5 is a bottom plan view thereof.

The broken line showing further details of the bottle are for illustrative purposes only and form no part of the claimed design.
